UNITED STATES PATENT OFFICE.

JOHN MARSTON GOODWIN, OF MOUNT VERNON, NEW YORK.

VEHICLE GIRDERS AND BULKHEADS.

No. 815,287.

Specification of Letters Patent.

Patented March 13, 1906.

Application filed June 7, 1905, Serial No. 264,092.

To all whom it may concern:

Be it known that I, JOHN MARSTON GOODWIN, a citizen of the United States, residing in the city of Mount Vernon, county of Westchester, and State of New York, have invented certain new and useful Improvements in Vehicle Girders and Bulkheads, of which the following is a full, clear, and concise specification.

10 My invention relates to the structural formation of cargo-carrying vehicles in general, and more particularly to the side girders and bulkheads of dumping-vehicles—such, for example, as the so-called "Goodwin" dumping-cars; and the invention consists in the formation, relative arrangement, and connections of the several parts to produce a maximum of rigidity and durability of the said side walls, together with extreme lightness in weight, cheapness, and facility of manufacture.

15 The principle of the invention and one mode of applying the same will be understood from the following description, in connection with the accompanying drawings, whereof—

20 Figure 1 represents a side elevation of a cargo-carrying vehicle, being specifically the type known as the "Goodwin" dumping-car, with intermediate portions broken away. Fig. 2 is a top plan of a portion of Fig. 1. Fig. 3 is a vertical transverse section on line 3 3 of Fig. 1, and Fig. 4 is a detail longitudinal section taken on line 4 4 of Fig. 2 in the direction of 25 the arrows.

25 The vehicle is comprised of two end members L or bulkheads, each properly braced and mounted upon the center sill or other suitable supporting-foundation. The sides 30 or side girders of the vehicle are supported at their respective ends upon these bulkheads, but may also be supported between their ends by intermediate bulkheads, such as K, or other suitable supporting means, as desired. Each side girder is composed generally of three main truss members, which extend the length of the vehicle, or at least span the distance between two of the means of support. The said truss members are so 35 arranged and connected that the uppermost member (designated 3) cooperates with a lower member 4 to form a trussed girder, of which the said members 3 and 4 are respectively the top and bottom chords, and the 45 third member or plate 5, which is disposed slightly inboard of the member 4, constitutes

another chord, which may be considered to be a top chord with respect to the member 4 and serves to brace the trussed girder against deviation in a lateral direction. The trussed girder is preferably arranged, as shown in Fig. 3, with its component members 3 and 4 located vertically above each other, so that it offers greatest resistance to vertical strains and is excellently adapted to carry the dead- 50 weight of the load in the vehicle, while the truss-bracing effect of the innermost member 5 resists the lateral or spreading action of the load.

55 The upper truss member 3 is shown herein as composed of a longitudinal sheet or channel-bar, which may and preferably does form an upper or vertical side wall for the vehicle. The lower truss member 4 consists of an ordinary beam or angle-iron cross-connected with member 3 by means of bracing members or hanger-stays 6, to be presently described. The innermost member 5 is shown herein as a longitudinal plate which is adjacent to the upper member 3 and parallel thereto as well as to the lower member 4. The plate 5 is preferably inclined inwardly, so as to form an inclined side or floor for the vehicle continuous and adjacent to the vertical wall provided by the upper member 3, and it is also 60 fastened to the trussed girder along the lower margin of its channel-bar 3, being spaced or braced from the lower member 4 of the trussed girder by means of the wedge-shaped castings or spacer-struts 7, interposed between said lower member and the lower divergent margin of the plate. In addition to the spacing or bracing functions of these struts 7 they also serve the additional function of forming supports for the pivoted 65 dumping-valves G, and for this purpose they are securely fastened to the inclined plate 5 and lower truss member 4 and also to the hanger-stays 6, the latter being purposely so located on the member 4 as to connect the upper and lower truss members at the points of attachment of the spacer-struts, which points obviously bear the greatest strain of the pressure on said valves. The hanger-stays are shown in Fig. 1 as formed of triangular sheets secured in the seam 3'. At the ends of the vehicle and next to the center bulkhead K these stays are preferably made longer than the intermediate ones.

70 The valves G, which preferably extend the entire length of the side girders and on both sides of the vehicle, are preferably pivoted

directly to the spacer-struts, as shown in Figs. 1 and 3, the connection being formed by a hinge-pin B', passing through the eyes of the spacer-struts, and hinge-links B B, located, 5 respectively, on opposite sides thereof. At its inboard end the valve is supported in the usual manner on the margin of a center detent-valve A, which swings on the central longitudinal shaft J, and when the valves on both sides are closed, as indicated in Fig. 3, the load is contained within or upon the walls 10 3 and 5 and the valves G and A.

In vehicles of comparatively short length the construction so far shown will be found 15 to be fully adequate for every practical use; but for longer vehicles the intermediate supports or bulkheads above referred to are desirable, and my invention involves the adaptation and connection of the same to the 20 girder construction already described. The central bulkhead K is formed of a sheet of metal extending transversely across the vehicle, with its upper flanged edge K' located somewhat below the horizontal plane of the 25 truss member 3 and preferably about flush with the angle-bars 4. The sheet extends vertically downward between the ends of valves G to a point (not shown in the drawings) where it is mounted on the sill or sills of 30 the vehicle in any ordinary manner. At each end its upper flange K' is cut away and a flanged gusset-sheet 8 is inserted between it and the members 3 and 5, flush with the plane of the bulkhead. Strips or cleats 9 are 35 then riveted over the flush edges on both sides, and angle-irons 10, which are bent to fit both the vertical and inclined wall, are riveted on opposite sides of the gusset in the angles between the same and the truss members 40 3 and 5, a filler 11 being inserted between the angle-iron and the channel-bar 3 to compensate for the thickness of the seam 3'. The angle-bars 10 also lap over the sheet K, similar to the cleats 9, to reinforce the same. 45 As shown in Fig. 4, the bulkhead-sheet K is provided with an attached flange or angle-iron K² complementary to its integral flange K', this being for the purpose of increasing the stiffness of the upper edge of the bulkhead, which by reason of its position inside of 50 the receptacle frequently encounters unusually severe strains and blows. The tensional strength of the cross member K, which is called upon to unite and bind together the 55 opposite side girders of the vehicle, is also reinforced by an angle-strap 12, fastened to the flanges K' K² and the flange 7' of the gusset-sheet and also by the bent T-strap 13, which laps over the upper flange of channel-bar 3 and the bent-over end 10' of the angle-iron 10 and secures these parts to the flange 7'. 60

Additional reinforcement of the several parts in any suitable manner may be employed, if desired, and the methods of forming and attaching the said parts may also be 65

varied without departing from the spirit and scope of this invention. Moreover, it is to be understood that while I have shown the side girder as preferably forming a vertical side wall of the vehicle such disposition of the 70 same is not essential, and the side walls may be also disposed flaring or tumbled home, as desired, it being only necessary in this regard that the upper truss member shall coöperate with its lower member to form adequate support for the hinges of the several dumping-valves. 75

Having described my invention, what I claim, and desire to secure by United States Letters Patent, is—

1. A dumping-vehicle having its sides respectively composed of three main longitudinal truss members, the uppermost thereof constituting a top chord with respect to the other two and the innermost of the remaining two members constituting a top chord with respect to the other, in combination with spacing means interposed between said two lower members, and bottom dumping-valves for the vehicle pivotally supported on said 90 spacing means.

2. A dumping-vehicle having sides respectively composed of a longitudinal trussed girder arranged to offer greatest resistance to vertical strains and with its upper portion constituting a side wall of the vehicle, in combination with a longitudinal inclined plate disposed inboard of said girder and constituting an adjacent side wall of the vehicle, spacing means interposed between said plate and the lower portion of said trussed girder and dumping-valves for the vehicle pivotally supported on said means.

3. A dumping-vehicle having its side girder composed of upper and lower longitudinal truss members and an inner longitudinal truss member, in combination with spacer-struts interposed between said inner member and the lower member, hanger-stays depending from said upper truss member and connected with said lower member in the region of its points of connection with said spacer-struts, and pivoted dumping-valves supported from said spacer-struts.

4. A dumping-vehicle having its side girder composed of an upper truss member constituting an upper side wall of the vehicle, a longitudinal plate secured to the lower margin of said member, constituting an adjacent side wall of the vehicle and hanger-stays depending from said upper member, in combination with spacers interposed between said stays and said plate and pivoted dumping-valves supported by said spacers.

5. A dumping-vehicle having a side girder composed of an upper truss member and an inclined plate secured thereto constituting a side wall of the vehicle, and hanger-stays depending from said member outboard of said plate, in combination with spacers inter- 130

posed between said hanger-stays and the plate and dumping-valves pivoted directly to said spacers.

6. A dumping-vehicle having a side girder composed of a longitudinal channel-bar constituting an upper side wall of the vehicle, an inclined longitudinal plate secured to the lower margin of said bar, hanger-stays also secured to said bar outboard of the plate, and spacer-struts secured between the hanger-stays and plate, in combination with an angle bar secured to the ends of said stays and dumping-valves directly pivoted to said spacer-struts.
- 15 7. A dumping-vehicle, having end bulkheads and side girders supported by their ends thereon, bottom dumping-valves pivotally connected with the lower margins of said side girders and convergent downwardly, in combination with an intermediate bulkhead below said girders, gusset-sheets disposed between said girders and the intermediate bulkhead flush with the plane of the latter, and angle-irons secured in the angles on opposite

sides of said sheets, said angle-irons overlapping the bulkhead and secured to the same and the side girders.

8. A dumping-vehicle, having end bulkheads and side girders supported by their ends thereon, inclined sides walls on said side girders, bottom dumping-valves pivotally mounted at the lower margins of said inclined walls and convergent downwardly, in combination with an intermediate bulkhead below said inclined walls, gusset-sheets disposed flush with the plane of said intermediate bulkhead for connecting the same with said side girders, and angle-irons secured in the angles on opposite sides of said sheet and overlapping and secured to said intermediate bulkhead.

In testimony whereof I have signed my name to the specification in the presence of two subscribing witnesses.
